PAGE 3

The dominant features of my design reside in the portions shown in full lines.

I claim:

The ornamental design for a snow blower, as shown and described.
